WINDING MACHINE

Ernst A. Nordberg, Sharon, Mass., assignor to
 Production Development Corporation, Canton,
 Mass., a corporation of Massachusetts

Application October 14, 1938, Serial No. 234,881

12 Claims. (Cl. 242—56)

The present invention relates to a winding machine for winding together in a roll ribbons of metallic foil separated by ribbons of insulating material.

While the machine may find useful application for other types of windings, it is particularly applicable to a machine for winding electrical condensers of both the paper and electrolytic types.

In electrical condensers there are provided two metallic foils or plates which are separated and insulated from each other by means of a dielectric element.

In the plate type of condenser the metal may be sheets of copper or aluminum separated by layers of mica, paper or other materials. Usually a number of layers of metal sheets or foil are used stacked one over the other with paper or other insulating means between. Each one group of the metallic plates or foil are connected to one electrical terminal and the other group to another electrical terminal, the important point being that the groups themselves are entirely insulated from each other. In the roll type of electric condenser the same general principle is followed and in the winding process therefore four or five sheets of material may be brought together. In each case the paper separating the foil with one set of foils being connected to one electrical terminal and the other set of foils connected to the other electrical terminal. In these wound condensers, the foil connected to one electrode or terminal, projects from one side of the roll, and the foil of the other electrode projects from the opposite side of the roll, the terminal connections being soldered or adhered on opposite ends of the completed roll.

The present machine is designed to produce the condenser windings and may also have means for finishing the electric connections by soldering or adhering terminals at the ends of the condenser roll. At the present time most machines for making condenser windings that are generally employed are so called semi-automatic, in that certain operations must be performed by hand, although the winding itself is usually done by adjusting the foil strips on a mandrel which is turned by an electric motor. There are a number of reasons why the machines for the most part are not fully automatic. In the first place the metallic foil and the paper are so thin that it is difficult to handle them with machinery. Both paper and foil easily tear, particularly in the types of machines that must be stopped and started for trimming the ends so that the end edges of the foil do not touch. If all the foil sheets are cut simultaneously and simply wound on the roll; the end edges of the foil are usually so close together that there is a possibility of frayed edges to make contact with each other or even if this is not possible, the ends of the foil

that carry opposite electrical potentials are closer than normal electrical specifications will allow. It is necessary to see in all cases that the ends of the paper generously cover the foil beneath so that there is no possibility of electrical connection or contact at the ends of the foil. In addition to this because the foil and paper are both very thin and flexible, the stopping and starting of the winding must be done slowly, and for this reason considerable time is used in this work in the winding of the condenser roll. It should also be noted that while it has been attempted to use means of pushing the foil in the feeding mechanism, this is extremely difficult and therefore the foil is preferably pulled or drawn and special effort must be made to have this occur uniformly and without change of speed.

According to the present invention there is provided a winding machine for winding together in a roll ribbons of metallic foil separated by ribbons of insulating material, including mandrels operating in cycles and adapted to continuously draw said ribbons from rolls or the like, said mandrels being arranged so that as the ribbons are severed from one mandrel they are simultaneously gripped by another mandrel to continue uninterruptedly the drawing of said ribbons.

In the present invention the condenser is entirely wound automatically, the only hand operation being the initial threading of the machine to put the strips in their proper position. When a complete set of rolls of paper and foil have been used, the machine is stopped and a new set is inserted, whereupon the machine will wind the entire set of supply rolls that feed it.

In the present invention both the starting and stopping of the foil have been avoided; the foil is drawn at a nearly constant speed in spite of the fact that the strips of foil and paper are cut from the roll as each condenser is being made and each condenser winding is finished in such a way that the paper overlaps the foil and prevents any electrical connection at the ends of the foil.

In accomplishing the results of the present invention, a machine is employed in which each operation is duplicated one on one half of the machine and the other on the other half of the machine in a phase displacement that is 180° apart. This will be explained more in detail later in the specification.

In this machine the proper lengths of foil and paper are established after the winding has commenced but before the winding is completed in such a manner that after the paper and foil for different individual windings are cut, winding will be completed without interruption in such a manner that no end edges of the foil can touch each other.

The invention will be further understood from

the description given below of an embodiment of the invention as illustrated by the drawings annexed hereto:

Figure 1 represents a perspective view of the entire machine as viewed from the right forward end.

Figure 2 shows a sectional view of the machine through the center on a slightly different scale from that shown in Figure 1 and looking from the opposite side of the machine from the perspective view taken in Figure 1.

Figure 3 shows a sectional view of a portion of the machine.

Figure 4 shows a plan view of a portion of the machine as viewed from the top of Figure 1.

Figure 5 shows a section taken on the line 5—5 of Figure 4.

Figure 6 shows a section of a detail on the line 6—6 of Figure 4.

Figure 7 shows a section of a detail on the line 7—7 of Figure 1.

Figure 8 shows a detail of the glue pot mechanism shown in Figures 1 and 2.

Figure 9 shows a side view of Figure 8 as viewed from the left side of Figure 8.

Figure 10 illustrates diagrammatically the cycle of operation of the machine.

Figure 11 shows diagrammatically the threading of the paper and foils for the winding as employed in the machine described in the previous figures.

Figures 12 and 13 show respectively how the ends of the foil and paper are severed for the beginning of the winding on the mandrel and the finishing of the winding on the roll.

Figure 14 shows a completed roll.

Figure 15 shows a modified method of winding in diagrammatic form.

Figures 16 and 17 illustrate the relative position of the foil and paper respectively at the beginning of the winding on the mandrel and the end of the winding on the roll when using the method shown in Figure 15.

Figures 18, 19 and 20 illustrate a further modification in the same respective relation as Figures 11, 12 and 13, and.

Figures 21, 22, 23, 24 and 25, illustrate still further modifications in the arrangement of the foil and paper at the beginning of the winding and at the completion of the winding.

Figure 26 shows a cross section substantially on the line 26—26 of Figure 4.

Figure 27 shows a sectional view through the lower portion of Figure 1 looking downwards towards the base of the machine, and.

Figure 28 shows a side elevation of one of the cams of the present machine.

In Figure 1 the machine is shown mounted on supporting legs 21 upon which rests the base plate 20 with guide rails 22—22 and 23—23. The guide rails 22 serve to guide the platform 24 at the right of the machine and the guide rails 23 serve in a similar capacity for the platform 25. Each of these platforms reciprocates back and forth on the rails 22 and 23, respectively, being forced in one direction by means of the cams 31 and 33, respectively, and being returned in the other direction by means of springs one of which is shown at 34. Each of these cams is so set and the other parts of the machine so arranged, that the movement of each platform and every operation associated therewith are similar but have a phase difference of 180° in the entire cycle of operation.

Each platform 24 and 25 has mounted thereon

a pair of guide rails, the guide rails for the platform 24 being indicated by 26 and 27. The guide rails for the platform 25 are at the back of the supporting bracket 35 and therefore not shown 5 in the drawings.

Moving on the guide rails 26 and 27 are the platforms 28, 29, supporting the upright plates 30 and 36, the latter of which carries the plates provided with rods to guide and control the strips 10 of foil and paper, the knife mechanism and the gluing mechanism which will be explained in detail later. The platforms 24 and 25 provide the longitudinal motion of the mechanism and the platforms 28 and 29 provide the transverse 15 motion of the mechanism for providing the complete winding procedure. The mechanism itself that produces the positioning, winding and guiding of the foil, will be more readily understood by considering initially the diagrammatic arrangement of Figure 11 on connection with the cross 20 sectional view of Figure 2 which shows the winding as taking place on the mechanism carried by platform 28. In the machine there are provided a set of fixed guide plates through which the 25 foil and paper are initially threaded. As indicated in Figures 2 and 11, the lower guide plates 40 and 41 are used for the paper strip 42, the next guide plates 43 and 44 for the foil 45. Through the third guide plates 46 and 47 there are threaded 30 two strips of paper 48 and 49. Above these are further guide plates 50 and 51 between which there is placed the foil 52 and a top pair of guide plates 53 and 54 holding the paper 55. The foil and paper pass between these plates being drawn 35 continually in the winding process without a great change in the rate of advance of either the paper or foil. On either side of the several guide plates there are positioned as shown in Figure 11, rods 1 to 10 carried by the supporting plates 30 on 40 either side of the machine. All of these rods advance forward in the winding process in the direction of the arrow A and some of these simultaneously move transversely to the direction of travel of the strips to lengthen in the proper amount the length of paper and foil as it is being wound on the roll, so that while the horizontal distances between the rods always remain the same, the vertical position with respect to each other may be changed as will be noted in the description below. For this purpose the rods 45 1, 2 and 3, 4, 5, 6, 7 and 8, retaining their permanent horizontal relationship are mounted directly in the upright bracket or plate 30, while those that move also in the vertical directions are 50 mounted in moving blocks or plates shown in Figures 2 and 4. Each moving block or plate 56, 56' has a projecting flange 57 which is dovetailed into an insert 58 mounted permanently or fixed in the plate 36. There are two of such plates for each side of the machine. These are 55 indicated in Figure 2 which shows the upper plate 56 and a lower plate 56' carried by the platforms 28, and upper plate 97 and lower plate 92 carried by the platform 29. Each of these plates upper and lower is moved substantially in the same manner towards a common center line by means of the cam plates 59 and 60 respectively and returned by means of the springs 61 and 62 shown in Figure 2 for the plates 97, 92. The 60 springs 61 and 62 pull the plates 56 and 56' in directions against the cams 59 and 60 and are fastened to fixed supports in the platforms as for instance the plates 36 and 36' and tend therefore always to separate the plates 56 and 56'.

Referring now to Figures 2 and 11, it will be

noted that each of the vertically moving plates carries four rollers or rods, the upper plate carrying the rollers or rods 63, 64, 65 and 66, and the lower plate carrying the rods or rollers 67, 68, 69 and 70. In Figure 11 the rods 65' and 66' are the same as the rods 65 and 66, but shown in a different position of the cycle and similarly the rods 69' and 70', though the primed numbers may be assumed if desired to refer to the corresponding rods on the pair of plates on the opposite side of the machine. In the initial position of the cycle the platform 28 with the plates 30 and 36 moves inwardly towards the center of the machine with the rods 65 and 66 and 69 and 70 assuming the positions indicated by the primed numbers 65', 66', 69' and 70'. Similarly the rods 1, 2, 3, 4, 9, 10, 7, 8, 6, 5, as well as the rollers 63, 64 and 67 and 68 are advanced forward to the center of the machine. The latter four rods are not indicated in their initial position of engagement but these are as will be noted from the arrangement in Figure 2 along the same horizontal lines respectively as the rods 65', 66' and 69', 70' which are rods 65, 66, 69 and 70, in their initial position as the platform 28 moves inward to the center of the machine in the beginning of the operating cycle. As the platform moves inward, all of the rods engage the foil and the paper in the position shown. Following the motion of the platform inward, all of the rods advance in the direction of the arrow A through the motion of the lower platform shown in Figure 1 as 24. This advance brings the rods 1 and 2 in the position of the rods 1' and 2', the rods 3 and 4 in the position of the rods 3' and 4', the rods 7 and 8 in the position of the rods 7' and 8', the rod 6 in the position of the rod 6', all of which move laterally or horizontally in Figure 11 without any vertical motion. The eight rods 63, 64, 65 and 66, 67, 68, 69 and 70, carried by the plates 56, 56', and the rods 5, 9 and 10, includes also vertical movement by the means which will be explained below.

As the platform 24 is advanced over the rails 22, the plates 56 and 56' from which extend covers 72 and 73, Figures 2 and 4, having rollers 74 and 75 bearing, respectively, on the cams 59 and 60 are acted upon by the cams 59 and 60 to force together these plates carrying rods 63, 64, 65, 66, 67, 68, 69 and 70, thus drawing the paper and foil together in preparation for threading the mandrel carried by the other platform 29 over the foil and paper strips which have been pressed together by the vertical motion of the upper and lower rods. Two mandrels 76, 76a are provided, one for each platform 28, 29. Figures 2 and 11 show the machine as winding on the mandrel carried by the platform 28. When the top and bottom plates 56, 56' have been moved together as they advance over the cams 59 and 60, the mandrel 76a supported by the platform 29 on the opposite side of the machine is advanced inwardly towards the center of the machine to cover or grip the foil and paper which has been pressed together. At the same time the rods carried by the platform 28 engage the strips of foil and paper. The mandrel itself is simply a rod with a slot and is shown as 76 in Figure 4 and as 76 and 76a in Figures 11 and 1 in which both mandrels are shown.

It should be noted in this respect referring to Figure 1, that as the platform 28 moves inwardly, the mandrel 76 mounted on it moves inwardly to enter between the opposite pair of plates 97, 92. As the platform 24 continues to move forward after the rollers have been brought together, the

covers 72 and 73 finally engage the projections 78 and 79 which force these covers which act against the springs 72' and 73' respectively and which are pivoted respectively at 80 and 81 downward and upward respectively at their forward edges forcing towards each other the knife plate 82 and the knife shoe 83 which sever the foil and paper. This occurs at the point indicated by the vertical arrow 84 in Figure 11. Up to this point in the cycle, the mandrel 76 has done all the winding, but at this point the mandrel 76a begins to turn and catch together the ends of the paper and foil. The winding of the mandrel 76 is completed in the manner that will be described later, while the mandrels 76 and 76a continue to advance with the advancing of the platforms 24 and 25. At the end of the winding operation, the platform 28 is thrown outwards by means of a lever 85 Figure 3, which hits against the abutment 85' at the bottom of the platform and the platform 24 is also returned by means of its spring which corresponds to the spring 34 of platform 25. In order to obtain the desired length of paper just before the foil and paper are severed, the rod 5 is moved downward by means of a cam plate 86 mounted on the bracket 35 in the center of the machine. This is accomplished by the arrangement indicated more clearly in Figures 4 and 5. The rod 5 is supported solely by a yoke 87 in which it is rigidly mounted. This yoke is carried by a plate 88 which works in grooves in the plates 30 and 36 and is urged upwardly by a helical spring 89 mounted in a top portion of one of the grooves. Projecting from the plate 88 is a roller 90, which, when it comes into engagement with the lower end of the cam plate 86, draws the rod 5 downward and lengthens the paper of the lower strip as indicated in Figure 11. This lengthening occurs at a point just before the cams 59 and 60 act to sever the paper. It will be noted from Figures 1 and 5 that the rod 5 and the corresponding rod 5a on platform 29 pass through slots 91 in plates 30 and 36.

It will also be noted from Figure 11 that the rods or rollers 9 and 10 move upward to the positions 9' and 10', respectively, just before the foil and paper are severed. These rollers 9 and 10 are indicated in Figures 2 and 5, Figure 2 also showing the rollers 9 and 10 corresponding to the position of the rollers 9' and 10' in Figure 11. The corresponding rollers of the other winding mechanism are also indicated in Figure 1 as 9a and 10a, respectively, and are shown in the upward position having been carried into this position by the movement of the lower block 92 on the cam 60. Movement of the lower block or plate 56' or 92 Figures 1, 4 and 6 upwards causes upward movement of a projecting bar 93' when the lower end of a slot 95' in the plate 56 or 92 bears against the bar. The projecting bar 93' is fastened to a slide 93 supported between the plates 30 and 36, so that the slide 93 is moved upward by movement of the plate 56 or 92. The slide 93 supports yokes 94 supporting in turn fixed positions the rods 9 and 10 which move in slots 90 and 95, respectively. The rods 9 and 10 are not mounted directly on the plate 56 since the motion of these rods vertically upwards is not as great as the motion of the rods or rolls 67, 68, 69 and 70, as will be readily seen from consideration of Figure 11.

As has been stated above, at the beginning of the operating cycle, all of the guide rods or rollers of the winding mechanism on one side of the machine are brought into the center in the posi-

tion illustrated diagrammatically in the left half of the Figure 11. The table or platform is then advanced towards the front part of the machine and the rods or rollers are thereby brought into their new position to lengthen out the strips of foil and paper so that the rolls will be properly wound. As this advance occurs all the strips of foil and paper are brought together in face to face relationship by the upper and lower blocks 56, 56' or 97 and 92 being forced together as the rollers 74 and 75 ride on the cams 59 and 60. When these blocks come together, then the paper is ready to receive the mandrel 76a or 76 of the other winding mechanism, which mandrel enters from the opposite side of the machine through the slot 98, as the opposite platform 29 or 28 shown in Figure 1 moves inwardly at the beginning of the cycle. At the beginning of the cycle therefore, the mechanism at one side of the machine has already assembled together the paper and foil so that the mandrel of the other side of the machine may enter over the paper and foil. Mechanism is also provided to align the slot or cut in the mandrel horizontally so that it will engage the foil and paper in the same horizontal position. This will be explained later. By the time that the mandrel on one side has engaged the strips on the other side, the papers and foils have already been adjusted to their proper lengths. The rod 5 or 5a has been moved downward by means of the cam plate 86 to the end of the slot 91 and the rods 9 and 10 or 9a and 10a have been moved upwards through the movement of the plate 92 or plate 56'. In advance of the mandrel entering at the beginning of the cycle, there is the second mandrel indicated in Figure 11 as 76. This has already completed part of its winding as the first mandrel is moving towards the center to enclose the foil and paper so that when the knife mechanism is operated by means of the projecting flanges 79 and 78 at the end of the cam plates 59 and 60, this mandrel has completed its winding except for the winding of the free ends severed by the knife blade. At the instant of cutting, the rods 63, 64, 65, 66, 67, 68, 69 and 70, hold the papers and foil together and the knife blade 82 comes down over the knife shoe 83 severing both foil and paper. Immediately after this the rollers 74 and 75 move beyond the cam plates 59 and 60, whereupon the springs 61 and 62 pull the blocks or plates apart freeing the foil and paper which is thereupon wound up and finished in the manner to be described. Following the completion of this travel as has been mentioned above, the lever 85 acts to throw outward the platform 28 and the associated spring (not shown but corresponding to spring 34) pulls back the platform 24 to the end of the machine. At the back end of the machine the cycle begins to repeat itself. The cycle begins by the mechanism that carries the plates or platform 28 inward to the machine. This is accomplished by means of the sprocket gear 99, Figure 3, which is continuously rotated from a power source and which carries a crank arm 100 from the end of which projects a pin 101 moving in a slot 102 in a bracket or support 103 on the platform 28 shown more clearly in Figure 1. As the pin 101 enters the slot 102 and the crank arm 100 rotates, the platform 28 is moved inwardly.

Before the platform 28 begins to move inwardly through the rotation of the sprocket gear 99, the spring corresponding to the spring 34 as has been mentioned above, returns the platform 24

to the back of the machine. Carried at the top of the plate 30 is a disc 104 which has four pins 105, 106, 107 and 108, arranged at the corners of a square on the disc. The frame of the machine 5 carries an arm 109 which is permanently fixed to it and this frame carries a projecting bar 110 having a V-shaped end 111 the width of the bar 110 being the width of the space between two adjacent pins. As the platform 24 moves backwards, the disc 104 which is positioned on the plate 30 so that it is in alignment with the bar 110, comes into the position as shown in Figure 1. This disc is mounted on the plate 30, or rather in an extension 112, Figure 4, supported from the plate 30 on a shaft 113 which on the inner side of the plate 30 carries the sprocket gear 114 having the sprocket chain 115 in mesh with it. This sprocket chain drives a second sprocket gear 116 which is on a shaft passing through the plate 36 which shaft is formed as the mandrel 76 at the other side of the plate. The gear ratio of the sprocket wheels 114 and 116 is in the ratio of 4 to 1 and the mandrel 76 is so aligned with respect to the disc 104 that between whatever pins the end 111 of the bar 110 comes, the slot in the mandrel will always be horizontal and be ready to receive the paper and foils.

As the platform 28 moves inwardly the sprocket wheel 118 also mounted on the same shaft as the sprocket wheel 114 rides into alignment with, 30 and then as the platform moves forward a very little into mesh with the sprocket chain 119 which rotates on the stationary bar 120, which bar 120 is a part of the frame of the machine. The sprocket chain 119 is driven from the power source through the sprocket chain 121 driving the sprocket gear 122 which rotates the shaft 123 mounted in the brackets 124 and 125 on the frame of the machine. The shaft 123 drives a gear 126 which in turn drives the gear 127 on the shaft 128 on which is mounted the sprocket gear 130 which drives the chain 119. The chain 119 is continuous and is driven around the pulleys 131, 132 and 133 situated in a rectangular fashion on the frame of the machine so that the sprocket chain 119 in the portion 134 is always in a horizontal position and adapted to mesh with the sprocket gear 118. As the platform 24 is moved forward, it will be evident that when the sprocket gear 118 is in mesh with the chain and moves with the same velocity or speed as the chain 119 or the horizontal portion 134, no movement of the sprocket gear 118 takes place. In this condition therefore the spindle or mandrel 76 or 76a remains stationary. The drive of the chain 121 will be more readily seen in Figures 2 and 3. The chain 121 engages at its lower portion the sprocket gear 99 previously mentioned at the inner side of the machine then passes around the sprocket 135 on the outer side and around the lower sprocket gear 136 which is mounted on the drive shaft 137 driven from the motor 138 through pulleys 139 and 140 by means of the belt 141. The pulley 140 is mounted at the end of the drive shaft, 137. The chain 121 after passing the lower sprocket wheel 136 extends upwards around the sprocket wheel 142 which corresponds to the sprocket wheel 99 and drives in a similar fashion the crank arm 143 having the pin 144 which engages the slot 145 corresponding to the slot 102 on the other side of the machine.

From the description given above, it will be seen that the speed of the chain 134 is dependent

entirely upon the gearing from the motor 138. The table or platform 24 is advanced by means of the cam 31 and the table 25 by means of the cam 33 which is similar to the cam 31 except displaced by a phase difference of 180° as has been previously stated. Both cams 31 and 33 are also driven from the motor. These cams are mounted on a drive shaft 146, see Figures 1 and 2, which shaft 146 is driven by the gear 147 which in turn is driven by the gear 148 mounted on the shaft 149 which is supported in the bearings 150 and 151 mounted in the bracket 152 which is attached by the flange 153 to the base 20 of the machine. The shaft 149 at its driven end has a toothed gear 155 which engages the gear 154 mounted on the drive shaft 137. It will be seen therefore that since the drive of the cams comes also from the drive shaft 137, that the various elements which are driven through this common drive shaft will remain in synchronism. Mounted also on the drive shaft 137 are the two heart shaped cams 156 and 157 on which ride respectively the rolls 158, 159 respectively projecting from the arms 160 and 161 respectively. These arms are secured to the shafts 162 and 163 which shafts 162 and 163 carry respectively the arms 164 and 165 which carry the bars 85 and 85' for throwing the platforms 28 and 29 respectively outward from the center of the machine at the end of the stroke. The bars 85 and 85' work against the lower sides of the platform, see Figure 3.

As the platforms 24 and 25 move to the end of their travel on the forward part of the machine, and while the platforms 28 and 29, respectively, are at their inward position the operation for winding the ends of the foil and paper subsequent to the cutting by the knives occurs. This is accomplished by means of the motors 166 and 167. These motors 166 and 167, see Figures 1 and 2, are mounted on a bracket 168 inclined at an angle downward at the top of the machine. These motors each carry cones 170 which cones come in contact with the wheels 171 of which there are two, one on each side of the machine. See Figure 4. The shaft 113 upon which the gear 114 is mounted carries a gear meshing with the gear 175 which is mounted on the cross shaft 172, which shaft also carries the wheel 171. This cross shaft 172 is mounted in the plates 173 and 174 between the plate 30 and the plate 112. See Figure 4. When the cone comes in contact with the wheel 171, the wheel 171 rotates, thus rapidly rotating the shaft 113 and driving the sprocket chain 115 to complete the mandrel winding completing the condenser. When the platforms 24 or 25 have progressed to the forward part of the machine, an arm 176 pivoted at 177 in the top of the frame, presses the roller 178 carried by the arm against the side of the condenser through the action of the spring 179 and keeps the ends of the foil and paper in place until they are cemented.

The gluing is accomplished by means of the glue pot 181 and its associated mechanism. See Figures 1, 2, 8 and 9. This glue pot has a roller 182 mounted on a shaft 184 supported in the end walls of the glue pot. This roller 182 engages in contact with a roller 183 mounted on a shaft 185 which is also supported in the walls of the glue pot. The glue pot has at the top an extending flange 250 which rests in the side walls or plates 92 or 56' of the frame in which the vertical moving rods previously described, are posi-

tioned. Pivoted to this frame or wall on the pivot 251, is a bar 252 which is linked with a second bar 253 which has its other end pivoted on the pivot 254 to the wall 255 of the glue pot. 5 A second bar 187 also pivoted to the side wall or plate 92 at 55' at the point 188 rests under the point of pivot 256 of the bars 252 and 253. The bottom end of the bar 187 resting on the plate 189 is supported by the pivoted cover plate 73. (See Figure 2.) The spring 257 exerts tension on the bar 252 to keep contact of the bars 187 and the joint at the pivot 256. At the end of the travel of the platforms 24 and 25 in a forward direction, when the two rollers 74 and 75 are forced towards each other (see Figure 2) at the end of the cam plates 59 and 60, the upper cover 72 and the lower cover 73, simultaneously with the action of the cutting by the downward motion of the cover 72 and the upward motion of the cover 73, cause the glue pot to slide slightly forward and bring the roll 183 in contact with the end sheet of paper, depositing sufficient glue upon the paper so that when the roll is finally completed, the roll 178 will force the end of the paper against the winding sealing or sticking it against the winding. Following this action as the platform 28 or 29 is drawn outward the winding is pushed in or forced from the mandrel by means of the collar 258 which fits over the mandrel 76 or 76a and is supported by the rod 259 which passes through the plates 36 and 30 and is mounted on an upright bracket 260 permanently fixed on the platform 24 by the base 261. When this occurs the roller 178 has been pushed beyond the position shown in Figure 2 so that the winding may roll down the chute 282. Beside the base plate 261 which mounts the bracket 260 upon the platform 24, there is indicated a block 262 shown in detail in Figure 7. This block carries a projecting bar 263 which rests in a recess in the block at the back end of which is a spring 264. The bar 263 may be rounded or pointed at the end and acts as a retaining device for the platform 28 inward and outward. For this purpose the platform 28 in its base carries a plate 265 which has two depressions 266 and 267, one near each end of the plate. In the backward motion of the platform the plate 265 comes to a position where the recess 266 is in contact with the rod 263, while at the end of the forward motion the rod 263 comes in contact with the recess 267.

The adjustment of the operation of the various elements to obtain the synchronism of the entire system will be understood more clearly from Figure 10 which shows a chart of the winding operations and other functions of the machine.

In this chart the abscissae represent an angular rotation of the cams 31 and 33 and the ordinates represent the distance of travel of the platforms along the length of the machine.

It will be noted from the previous description that the platform 24 for instance, Figure 1, remains stationary as the platform 28 is brought inward to the center of the machine. The platform 24 then moves forward at a speed controlled by the cam 31 to the end of the stroke, whereupon the platform 28 is thrown outward and returned to its initial position. This cycle of operation may be followed on the chart of Figure 10. The cycle itself may be followed by the full line curve B. This begins at the point marked zero on the ordinate line at the left.

As the cam rotates initially, one of the platforms 28 or 29 for example 28, is brought inward to the center. During this inward movement, the cam 31 associated with the platform 28 has progressed in its angular rotation from the point O to C, and the other cam 33 displaced 180° has progressed from E to F with the platforms 28 and 29, S distance apart and stationary with respect to forward motion along the length of the machine. Also during this time a great deal of the winding has been taking place on the first mandrel, that is the mandrel associated with the platform 29. At the points C and F the cams commence the forward motion of the platforms keeping the distance apart S constant, and soon accelerate the speeds of motion of the two platforms making the portions of the curve after the points C and F at the points D and G for instance, the same velocity as that of the lines A and A' which are the same as the velocity of the chain 119 in the portion 134. Both platforms continue to move forward at the velocity A to the points K and L. While this occurs, the sprocket 118 associated with the platform 28 engages the chain 119 at the point H, and the other sprocket associated with the platform 29 is still engaged in a chain corresponding to the chain 119 on the other side of the machine, and since both platforms are moving forward at the velocity A, no winding takes place on either mandrel. The point J corresponds to the point H. Between the points J and L while the platforms are moving at the velocity A, cutting takes place. Immediately after cutting both platforms stop moving forward as shown between the points K and M and the points L and N. This allows the mandrel associated with the platform 28, that is, the rear mandrel to rotate a little more than half a turn so as to bind the paper and foil to the mandrel, and the length of the paper and foil wound is proportional to the difference in the heights of the ordinates at M, between the line A and the curve B indicated as W on the graph. From M and N to P and Q, both platforms advance together at the same constant separation S, during which time the upper and lower plates 92 and 97 which had dimensioned the paper and foil in the region between P and E separate and the sprocket associated with the first platform leaves the chain 119. The second platform 28 advances from P to E by almost any desired curve, while the first platform 29 advances from Q to R, during which time the cone 170 is engaged with the wheel 171 and finishing takes place from Q to some point between T. The platform 29 then moves out from the center between T and R and the winding is ejected and then this first platform 29 returns to the point O to become the second platform in repeating this cycle of operation. The only considerations of the curve from P to E are that the second platform never gets nearer to the first platform than the distance S, and the slope of the curve at any point between P and E never exceeds the slope of the line A to prevent unrolling of the winding being wound.

From a consideration of the description above, it will be noted that the velocity of the paper and foils substantially remains constant as it is drawn from the rolls upon which the paper and foils are originally contained. In effecting this result the linear velocity of the chain 119 in the portion 134 is always kept at a constant velocity. The motion of the platforms 28 and 29 forward vary from time to time in accordance with the cams which control their forward motion. If V_p is

the instantaneous forward velocity of the platform, and V_m is the instantaneous velocity of the mean mandrel periphery, then the relationship between the three elements may be expressed by the equation $V_f = V_p + V_m$, where V_f is the velocity of the foil and paper.

After the mandrel has gripped the foil and paper, if the platform moves forward at the same velocity as the sprocket chain 119 in the portion 134, then no winding of the mandrel takes place, and the only movement of the foil is that due to the movement of the platform which therefore, at that instant must be made equal to the desired constant velocity of the foil and paper. Therefore the velocity of the chain is made equal to this desired velocity of the foil and paper. When the platform moves at a less velocity than a sprocket chain, then the difference is made up by the winding of the mandrel. By proper choice therefore of the fundamental driving speed of the entire system, the desired constant velocity of drawing of the paper may be changed from any one constant velocity to any other constant velocity. If it is desired to increase the length of the winding or to decrease the length of the winding, the velocity of the chain 119 in the portion 134 is varied accordingly to increase or decrease the speed of the sprocket chain in proportion to the increase or decrease of the lengths of the winding. In such a case the maximum platform speed is made equal to the chain speed by proper choice of cams.

The chart shown in Figure 10 illustrates diagrammatically the cycle of operation of the machine. Figures 15 to 25 show modifications. Before describing this, it is well to mention Figures 12, 13 and 14, which relate to the winding of Figure 11. Figure 12 illustrates the position of the paper and foil of Figure 11 after the condenser winding has been severed. It will be noted that the two inner papers 48 and 49 and the two outer papers 42 and 55 are longer than the foil 45 and 52. This is brought about by the rollers 9 and 10 moving upwards lengthening the paper 48 and 49 and because of the rods 1 and 2 which are not carried by the blocks that come together but remain in permanent position in the side plates, as for instance 30 and 36. The foils 45 and 52 are shorter therefore than the four paper sheets at the inside of the winding. When therefore these papers are twisted by the mandrel, the foils are insulated from each other. For the other end of the severed foils and papers, the rod 2 lengthens out the paper 55 as compared to the foil 52 and similarly the two papers 48 and 49. The bottom paper sheet 42 is considerably lengthened by the rod 5 being pulled downward in the position indicated in 5' so that the end is completely sealed and insulated by the paper sheet.

In Figure 14 the completed winding is shown. In this it will be noted that one foil sheet, which may be 52, projects from the left end of the winding, while the foil sheet 45 projects from the right end of the winding.

In Figures 15, 16 and 17, a different arrangement of mandrel and rods is illustrated, following in general however the same principles. In this arrangement the two foil sheets 200 and 201 representing the two electrodes of the condenser are separated by the two sheets of paper 202 and 203, and covered respectively by the single sheets 204 and 205. In this case the rods 206, 207, 208 and 209, are carried by the upper plate 56 or 97.

and the rods 210, 211, 212 and 213, by the lower plate. The rods 208' and 209' correspond to the rods 208 and 209 in the plate on the opposite side of the machine, and the rods 212' and 213' to the rods 212 and 213 on the other side of the machine. The rod 217 is drawn downward to lengthen the inner paper sheet 205. The position of the winding in Figure 15 shows the foil and paper at the point where it is being severed as indicated by the arrow 218. In this position the inner ends of the paper 204, 202 and 203 have their edges severed in the same straight line with the foil 200. The other foil 201 however is shorter. The paper 205 is the same length to the left of the cut in Figure 15 as the other papers, so that the papers 205 and 203 cover completely the foil 201 as the first portion of the turn is given to the mandrel 219.

At the end of the winding, the severing of the foil and paper causes the foil and paper to assume the positions indicated in Figure 17 from which it will be seen that the inner paper 205 is longest, the foil 201, shortest, and the other foils and papers of the same length but longer than the foil 201. Figures 18, 19 and 20, illustrate an arrangement in which only one half of each plate is movable, namely the lower half. In this case the plate which moves vertically up and down contains the rollers 220, 221, 222 and 223. The paper and foil after severing by the knife blade which is at the position of the arrow 227 is indicated in Figures 19 and 20. Here the mandrel 228 has first a short end foil 229 and then two papers 230, 231, a second foil 232 and two papers 233 and 234, all of the same length, that is coming to the same edge together. At the other ends the foils and papers are in the position indicated in Figure 20 with the foil 229 shorter the paper 230, 231, 233 and the foil 232 longer than the foil 229, but all of the same length with the end paper 234 longest of all the sheets.

Figures 21, 22 and 23 show a still further modification which is similar to that shown in Figures 18 to 20 inclusive, except that there is a single inner paper sheet 234 and an outer paper 235. The sheet 235 has the same length as the foil sheet 229 and both of these elements are shorter than the papers 230, 231, 234 and the foil 232. Figures 24 and 25 illustrate initially end insulation of the winding in the first half turn of the mandrel when winding clockwise or counter clockwise and having the papers and foil arranged as in Figure 21.

It should be noted that the cycle of operation is duplicated on both sides of the machine and that therefore both sides of the machine are symmetrical with the center line and this follows without any exception so that the parts which have been described with reference to the right side of the machine or the left side of the machine are duplicated exactly throughout the machine. The two cam plates 31 and 33 are also similarly constructed but act in such a manner that the cycle of operation of one of the platforms reciprocated by one of the cams always remains relatively advanced over that of the other platform. This advance in cycles in the present layout is at 180° and while other degrees of advance may be suitable, the relationship of the cycles in the present layout has proven to be the best.

As has been mentioned initially in the discussion of the apparatus of the present application, the cam speed is such that together with the ver-

tical movement of the various rods and the relative motions of the sprocket gear 118 with the chain 119, a substantially constant drawing of the foil and paper occurs. At the time when no winding takes place on one mandrel, the winding is taking place on the mandrel in advance of this and as soon as the paper and foil are severed, the mandrel in the rear continues to wind the paper and foil at substantially the same speed. Under these conditions the tension on the foil and paper is always nearly the same and the foil and paper are always being drawn so that great forces due to acceleration are never present. Nor is there much slack due to slight differences in speeds, since regardless of the winding of each individual mandrel, the paper and foil are always progressed forward at substantially the same speed.

Having now particularly described and ascertained the nature of my invention and in what manner the same is to be performed, I declare that what I claim is:

1. A machine for making condenser windings of the type described in which foil and paper is supplied from continuous rolls of material and the windings comprise a plurality of sheets of condenser foil and paper, a mandrel for receiving said sheets, means providing both rotation of said mandrel for winding said sheets and translatory motion of said mandrel, the rotation and translatory motions having a relationship to each other such that the feed of said sheets is substantially constant, and means for severing the windings from said sheets during the translatory motion of said mandrel.

2. A machine for making condenser windings of the type described in which foil and paper is supplied from continuous rolls of material and the windings comprise a plurality of sheets of condenser foil and paper, a pair of mandrels adapted to receive said sheets, means alternately moving said mandrels into engagement with said sheets, means providing both rotation of said mandrels for winding said sheets and translatory motion of said mandrels, the rotation and translatory motions having a relationship to each other such that the feed of said sheets is substantially constant and means for severing the windings from said sheets during the translatory motion of said mandrel.

3. A machine for making condenser windings of the type described in which foil and paper is supplied from continuous rolls of material and the windings comprise a plurality of sheets of condenser foil and paper, a pair of mandrels adapted to receive said sheets, means alternately moving said mandrels into engagement with said sheets at relatively the same point in the operation of the machine and means providing similar cyclic operation of said mandrels including means providing both rotation of said mandrels for winding said sheets and translatory motion of said mandrels and means severing the windings from said sheets during a period in said cycle in which both said mandrels have translatory motion.

4. A machine for making condenser windings of the type described in which foil and paper is supplied from continuous rolls of material and the windings comprise a plurality of sheets of condenser foil and paper, a pair of mandrels adapted to receive said sheets, means for moving said mandrels into engagement with said sheets at relatively the same point in the operation of the machine in alternate succession,

means providing a cycle of operation similar for each mandrel, said cycle comprising translatory and rotational motion of said mandrel alternately, said translatory motion of each mandrel having coinciding periods, and means severing the windings from the sheets during said translatory motion.

5. A machine for making condenser windings of the type described in which foil and paper is supplied from continuous rolls of material and the windings comprise a plurality of sheets of condenser foil and paper, a pair of mandrels adapted to receive said sheets, means for moving said mandrels into engagement with said sheets at relatively the same point in the operation of the machine in alternate succession, means providing a cycle of operation similar for each mandrel, said cycle comprising translatory and rotational motion of said mandrel alternately, said translatory motion of each mandrel having coinciding periods, and means severing the windings from the sheets during said translatory motion, the cycle with respect to each mandrel being such that a portion of the forward motion of each mandrel occurs at the same time and with the same velocity.

6. A machine for making condenser windings of the type described in which foil and paper is supplied from continuous rolls of material and the windings comprise a plurality of sheets of condenser foil and paper, means for guiding said sheets in a continuous feed through said machine, a pair of mandrels adapted to receive said sheets, means for moving said mandrels from opposite sides of the sheets into engagement with the sheet at relatively the same point in the operation of the machine at alternate intervals, means providing a cycle of operation for each mandrel including its inward operation to engage the paper comprising, both translatory and rotational motions for said mandrels, a portion of said translatory motion occurring at the same time for each mandrel, and means for severing said windings from said sheet at a point in the translatory motion of said mandrels while each engages said sheets.

7. A machine for making condenser windings of the type described in which foil and paper is supplied from continuous rolls of material and the windings comprise a plurality of sheets of condenser foil and paper, means for guiding said sheets in a continuous feed through said machine, a pair of mandrels adapted to receive said sheets, means mounting and moving said mandrels inwardly to engage said sheets and longitudinally with said sheets, and means in part included in said previous means providing also rotational motion for said mandrels and cam means providing cyclic operation of the rotation and translatory motion of said mandrels whereby a portion of the translatory motion of said mandrels occurs simultaneously and means for severing the winding from said sheets during the engagement of said mandrels and during their translatory motion.

8. A machine for making condenser windings of the type described in which foil and paper is supplied from continuous rolls of material and the windings comprise a plurality of sheets of condenser foil and paper, means for guiding said sheets in a continuous feed through said machine, a pair of mandrels adapted to receive said sheets,

means mounting and moving said mandrels inwardly to engage said sheets and longitudinally with said sheets, and means in part included in said previous means providing also rotational motion for said mandrels and cam means providing cyclic operation of the rotation and translatory motion of said mandrels whereby a portion of the translatory motion of said mandrels occurs simultaneously and means for severing the windings from said sheets during the engagement of said mandrels and during their translatory motion, the relation between the translatory and rotational motion of the mandrels being such that constant feed is obtained.

9. A machine for making condenser windings of the type described in which foil and paper is supplied from continuous rolls of material and the windings comprise a plurality of sheets of condenser foil and paper, means for guiding said sheets in a continuous feed including means operating substantially at right angles to the normal feed of said sheet for altering the length of feed of some sheets with respect to the others.

10. A machine for making condenser windings of the type described in which foil and paper is supplied from continuous rolls of material and the windings comprise a plurality of sheets of condenser foil and paper, a plurality of guides through which said sheets feed and are gathered together in face to face relation, a mandrel, means for aligning the mandrel to engage said assembled sheets edgewise, means for moving said mandrel transversely towards said sheets for engaging the same, and means for moving said mandrel in the direction of the feed of said sheets and rotating the same to hold said sheets.

11. A machine for making condenser windings of the type described in which foil and paper is supplied from continuous rolls of material and the windings comprise a plurality of sheets of condenser foil and paper, a plurality of guides through which said sheets feed and are gathered together in face to face relation, a mandrel, means for aligning the mandrel to engage said assembled sheets edgewise, means for moving said mandrel transversely towards said sheets for engaging the same, means operatively engaging said mandrel after it has engaged said sheets for rotating the mandrel and means advancing said mandrel in the forward direction of feed of said sheet, said last two means reacting with one another to vary the speed of rotation of said mandrel.

12. A machine for making condenser windings of the type described in which foil and paper is supplied from continuous rolls of material and the windings comprise a plurality of sheets of condenser foil and paper, a plurality of guides through which said sheets feed and are gathered together in face to face relation, a mandrel, means for aligning the mandrel to engage said assembled sheets edgewise, means for moving said mandrel transversely towards said sheets for engaging the same, means for varying the position of some of said guides in a direction away from the direction of normal feed of the sheets whereby the feed of some sheets are lengthened over that of the other, said guides being positioned so that the sheets of paper are longer than the sheets of foil both for a winding being finished and a winding being made.

ERNST A. NORDBERG.
